PIEZOELECTRIC CRYSTAL HOLDER

Rudolf Bechmann and Wilhelm Schneider, Berlin,
Germany, assignors to Telefunken Gesellschaft
für Drahtlose Telegraphie m. b. H., Berlin, Ger-
many, a corporation of Germany

Application October 12, 1935, Serial No. 44,674
In Germany November 6, 1934

9 Claims. (Cl. 171—327)

This invention relates to a new and novel holder for a piezo-electric crystal oscillator.

This application is a continuation in part of application Serial No. 738,454, filed August 4, 5 1934.

In the above-mentioned patent application, a holder or setting means for oscillators of the piezo-electric crystal type has been disclosed, the essential feature of which is that the crystal and 10 the electrodes are embedded inside a casing consisting of ceramic material. The present invention discloses a further improvement of the said crystal holder which is predicated upon the following considerations.

15 The temperature coefficient of a crystal device consists of the temperature coefficient of the crystal itself, and the temperature coefficient of the crystal holder. A number of suggestions are known from the prior art with a view to minimizing the temperature coefficient of the crystal itself by choosing a suitable cut. Hence, still further decrease of the temperature coefficient of the entire device is obtainable only by a reduction 20 of the temperature coefficient of the crystal holder. Especially in the case of holders of such crystal oscillators as are called upon to insure an extremely high-frequency stability or constancy, for instance, when employed as crystal monitors in connection with transmitters or as 25 quartz "clocks", it is of essential importance that the temperature coefficient be kept small.

As a general rule, the electrodes are at an extremely small distance from the surfaces of the crystal; but this interval of space and its stability or preservation is essential from the viewpoint of the oscillatory state and the frequency 35 stability of the crystal. As a result, even changes in the distance should be avoided which, per se, would be small, but which would exercise a high 40 percentage influence. In fact, it has been for this reason that the earlier filed patent application contains the instruction that the electrodes should be confined inside a casing consisting of ceramic material, the underlying idea being to 45 utilize the small temperature coefficient of ceramics rather than the higher temperature coefficient of metal.

Now, according to this invention, not only for the casing, but also for a portion of the principal 50 mass of the electrodes, ceramic material is employed, such necessary metallic surface portions of the electrodes as are placed opposite the crystal being, if desired, metallized for the purpose of obtaining electric conductivity. In order to pre- 55 clude soiling of the electrode surfaces by atmos-

pheric agencies, for these are liable to cause irregularities of the surface and partial changes in the interelectrode distance, it is recommended to use for metallization the surface with a kind of metal, preferably chromium, that will be 5 stable both in reference to atmospheric and humidity actions.

One exemplified embodiment of the invention is illustrated in the drawing in which Fig. 1 shows a plan view of the crystal holder, a portion of which is broken away to show the inner construction; Fig. 2 is a cross section of Fig. 1; Fig. 3 is an enlarged detailed portion of Fig. 2. The ring-like casing made of ceramic material 1, surrounds the oscillator crystal 2 which is planar or laminar in form, and which is secured by centering ring 3. Supporting of the crystal is effected in this manner that the crystal plate has a peripheral groove or slot into which engage yieldingly or elastically the peaks or supporting 15 studs 3' inserted in the centering ring 3. The latter is clamped fast on both sides by insulating rings made of ceramic material 4, and the electrode holder means 5. These latter, as shown in the drawing, are secured on the casing 1 by means of a screw threaded joint. The electrodes designated by 6 are of ceramic material and they are metallized upon the working or active surfaces 6' which are located opposite the crystal. To insure adjustment of the distance between the electrode surfaces and the crystal, the electrode bodies 6 are embedded in metal rings or caps 7 which have a fine-pitched male screw thread 7', by means of which they are adjustable in the bushing-like electrode holders 5 which have female thread. In order to fix the distance once 20 adjusted, there is provided the screw-threaded rings 8 arranged on both sides. The ceramic casing caps or cover pieces 10 on both sides are 25 united with the casing 1 by means of screws 12. The preferable plan is to make the casing fastening screws 12, as shown, in such a way that one and the same bolt serves to secure, on the one hand, the electrode holder 5, and, on the other hand, the casing cap 10. 30

For the purpose of establishing conductive connection with the electrode metallized surfaces, there is provided a metallic spindle 9 which is fixed within the electrode body 6 and in conductive connection with the electrode metallized surfaces, said spindle 9 being maintained in electrical contact with a lead-in supported in cap 10. In order to insure safe contact-making, lead 11 is 35 made yielding such that its spindle stud 11' is pressed against the end surface of conductor 9 40 45 50 55

by virtue of spring 13 applying pressure to member 9.

Having thus described our invention, what we claim is:

5 1. A piezo-electric crystal holder comprising an insulating casing, a crystal within said casing, a supporting member for said crystal, two insulating members located at each side of said crystal, said insulating members having their surfaces 10 that face said crystal coated with metal to act as an electrode for said crystal.

2. A piezo-electric crystal holder comprising an insulating casing of ceramic material, a crystal within said casing, a supporting member for 15 said crystal, two insulating members of ceramic material located at each side of said crystal, said insulating members having their surfaces that face said crystal coated with metal to act as an electrode for said crystal.

20 3. A piezo-electric crystal holder comprising an insulating casing, a crystal within said casing, a supporting member for said crystal, two adjustable insulating members located at each side of said crystal, said insulating members having their 25 surfaces that face said crystal coated with metal to act as an electrode for said crystal, and means for connecting said metal surfaces outside of said casing.

4. A piezo-electric crystal holder comprising 30 a ring-like insulating casing having removable end caps, a crystal within said casing, a supporting member for said crystal, two insulating members located at each side of said crystal, said insulating members having their surfaces that 35 face said crystal coated with metal to act as an electrode for said crystal.

5. A piezo-electric crystal holder comprising an insulating casing having removable end caps, a crystal within said casing, a ring-like supporting member for supporting and surrounding said crystal, securing means whereby said supporting member is secured within said casing, two insulating members located each side of said crystal, said insulating members having their surfaces 40 that face said crystal coated with metal, each of said metal surfaces acting as an electrode for said crystal.

45 6. A piezo-electric crystal holder comprising an insulating casing having removable end caps, a

crystal within said casing, a ring-like supporting member for supporting and surrounding said crystal, securing means whereby said supporting member is secured within said casing, two adjustable insulating members located each side of said crystal, said insulating members having their surfaces that face said crystal coated with metal, each of said metal surfaces acting as an electrode for said crystal.

5 7. A piezo-electric crystal holder comprising an insulating casing having removable end caps, a crystal within said casing, a ring-like supporting member for supporting and surrounding said crystal, securing means whereby said supporting member is secured within said casing, two insulating members located each side of said crystal, said insulating members having their surfaces that face said crystal coated with metal, each of said metal surfaces acting as an electrode for said crystal, and means passing through the end 10 of said casing for connecting said metallic surfaces outside of said casing.

15 8. A piezo-electric crystal holder comprising an insulating casing having removable end caps, a crystal within said casing, a ring-like supporting member for supporting and surrounding said crystal, securing means whereby said supporting member is secured within said casing, two insulating members located each side of said crystal, said insulating members having their surfaces 20 that face said crystal coated with metal, each of said metal surfaces acting as an electrode for said crystal, and means passing through the end of said casing for connecting said metallic surfaces outside of said casing.

25 9. A piezo-electric crystal holder comprising an insulating casing having removable end caps, a crystal within said casing, a supporting member surrounding said crystal, securing means whereby said supporting member is secured within said casing, two insulating members having threaded bushings secured to each end thereof for adjusting said members with respect to said crystal, said insulating members having their surfaces 30 that face said crystal coated with a metal to act as an electrode for said crystal.
